UNITED STATES PATENT OFFICE.

FRANK CANFIELD, OF DENVER, COLORADO, ASSIGNOR TO THE WESTERN WIRE FENCE COMPANY, OF DENVER, COLORADO.

WIRE-FENCE TOOL.

SPECIFICATION forming part of Letters Patent No. 718,243, dated January 13, 1903.

Application filed January 11, 1902. Serial No. 89,310. (No model.)

To all whom it may concern:

Be it known that I, FRANK CANFIELD, a citizen of the United States of America, residing at Denver, in the county of Arapahoe and State of Colorado, have invented certain new and useful Improvements in Wire-Fence Tools; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to improvements in tools for applying clips or fastening devices to the wires and stays at their intersections in wire-fence constructions, my object being to provide a device of this class which shall 20 be simple in construction, the elements being so combined and arranged as to exert great power and possessing the requisite durability and efficiency for a tool of this class; and to these ends the invention consists of the features, arrangements, and combinations hereinafter described and claimed; all of which will be fully understood by reference to the accompanying drawings, in which is illustrated an embodiment thereof.

25 30 In the drawings, Figure 1 is a top or plan view of my improved tool. Fig. 2 is a section taken on the line $x-x$, Fig. 1. Fig. 3 is a front end elevation of the tool with the detachable die-plate removed. Fig. 4 is a section taken on the line $y-y$, Fig. 1. Fig. 5 is a section taken on the line $z-z$, Fig. 2. Fig. 6 is a perspective view in detail of a split keeper applied to each die member. Fig. 7 illustrates a wire and stay fastened by the 35 40 clip members, showing the result of the operation of my improved tool. Fig. 8 is a face view of the detachable abutment-plate.

The same reference characters indicate the same parts in all the views.

45 Let the numeral 5 designate the body or frame of the device, in which is incased a reciprocating plunger 6, provided at its forward extremity with a die 6^a, which is fast therein and provided with a counterpart cavity 6^b, adapted to receive the central part of one of the members 7 of the fastening-clip. The

face of the die around the central cavity is also provided with four recesses 6^d, adapted to receive the projections of the clip members forming the seats for the wire and stay. 55 The die has a central opening in which is placed a keeper 8, slotted or bifurcated to straddle a central plate 9, fast in the die. The forward extremity of the keeper passes through an opening in the central part of the 60 clip member and holds the said member temporarily in place preparatory to applying the clip to the wire and stay. The rear extremity of this keeper is acted on by one extremity of a coil-spring 10, whose opposite extremity 65 engages a stop-pin 12, fast in the plunger. This spring normally holds the keeper in the protruding position—that is to say, with its forward extremity projecting forwardly from the bottom of the cavity 6^c—in order that it 70 may enter the opening in the clip member and support the latter in place. As pressure is applied and the wire is forced rearwardly into the cavity of the clip member the keeper is forced rearwardly against this spring, compressing the latter. The body or framework 75 80 85 90 95 100 5 of the device is composed of two side channel-bars 5^a, connected by top and bottom plates 5^b and 5^d, respectively. The forward extremities of the side bars 5^a are horizontally slotted in the plane of two of the recesses 6^d, as shown at 5^c, to receive the wire 13. The bar extremities are also provided with vertical grooves A, intersecting the slots 5^c at right angles, adapted to receive a plate 14, forming an abutment cooperating with the plunger in applying the twin clip members to the wire and stay. The vertical sides of this plate 14 engage the grooves of the bars 5^a, thus making this plate 14 a fixed or rigidly-detachable die-plate. This plate is also provided with shoulders 14^a, which support it in position, preventing it from slipping downwardly through the bars.

The plate 14 is provided with a central die 95 member 14^c, provided with a central cavity 14^d and lateral recesses 14^e to receive the clip members 7. This die member 14^c is substantially of the same construction as the die member 6^a, carried by the plunger. The die 14^c is provided with a central opening, through which is passed a slotted keeper 15, which

straddles a plate 16, fast in the die. The parts of the keeper on opposite sides of the plate normally spring outwardly, whereby the keeper is self-retained in the die member. It, 5 however, yields to forward pressure in order to allow the stay 17 to move forwardly into the central cavity of the clip member.

The means for and the manner of operating the plunger will now be described. Pivotally connected with the pin 12 on opposite sides of the plunger, which is recessed or cut away for the purpose, are two links 18, whose opposite extremities are connected, by means of a pin 19, with the bifurcated extremity of 15 a hand-lever 20, fulcrumed at 21 between the rear extremities of the bars 5^a. The lever 20 and the links form a toggle-joint for operating the plunger. Another hand-lever 22 passes between the arms 20^a of the bifurcated 20 portion of the lever 20 and is pivotally connected with the pin 19, its forward extremity passing between two links 23 and under a roller 24, mounted on a pin 25, connecting the upper extremities of the links, whose 25 lower extremities, which protrude through openings formed in the bottom plate 5^d, are connected by a pin 26, passed through openings in the link extremities outside of the said bottom plate.

30 Preparatory to using the tool the die-plate 14 is removed from the bars 5^a and a clip member 7 placed against the die 6^a, the forward extremity of the keeper passing through an opening in the center of the clip member and 35 supporting it in place, the levers 20 and 22 being separated to withdraw the plunger or move it rearwardly sufficiently for the purpose. The tool is then moved to a position causing the wire 13 to enter the slots 5^e of 40 the channel-bars and engage the clip member as it is held in the die. The stay 17 is placed in position forward of the wire. Another clip member 7 is then placed against the die 14^c of the plate 14, the keeper 15 being pushed 45 rearwardly to enter the central opening of the said clip member. The die-plate 14 is then dropped to position between the channel-bars, (see Figs. 1 and 2,) after which the two clip members 7 are in alinement with each other 50 on opposite sides of the wire and stay. The hand-levers 20 and 22 are then moved toward each other from the dotted-line position shown in Fig. 2 to the full-line position in the same figure. As the lever 22 bears upon the roller 24 from beneath, which roller forms its fulcrum, the toggle members composed of the links 18 and the bifurcated forward part of the lever 20 are made to approach a straight-line position, (see Fig. 2,) whereby the plunger 55 is forced forwardly by the toggle action, and consequently with great power, toward the abutment die-plate 14, whereby the wire and stay are bent outwardly in opposite directions into the cavities or central openings of 60 the clip members, the said members being at the same time forced together and the arm 7^a of each member made to clasp or embrace the

other member, whereby the two members are held securely in place and the wire and stay fastened firmly together.

Having thus described my invention, what I claim is—

1. In a wire-fence tool, the combination with a frame, of a plunger slidable therein and provided with a die whose face is provided with a central cavity and lateral recesses leading outwardly from said cavity, an abutment-plate detachably connected with the frame in front of the plunger and provided with a central cavity and lateral recesses similar to those formed in the plunger, the dies of the two parts being in alinement and arranged to coöperate, and suitable means for actuating the plunger. 75

2. In a wire-fence tool, the combination with a frame, of a plunger arranged to reciprocate therein and provided with a die having a central cavity and lateral recesses, the die being provided with a central opening, a spring-held keeper inserted in said opening 90 and normally projecting into the cavity of the die, an abutment-plate detachably mounted on the frame forward of the plunger and provided with a die in alinement with the plunger-die, the die of the abutment having a central cavity, lateral recesses, and an axial opening, a keeper movable in said opening adapted to protrude into the central cavity, the two dies being arranged to coöperate, and suitable means for actuating the plunger. 100

3. In a wire-fence tool, the combination with a frame, of a plunger arranged to reciprocate therein and provided with a die in its front face, said die having a central cavity and lateral recesses adapted to receive the 105 wire clip member, the forward extremity of the frame being slotted on opposite sides of the plunger to receive the wire, an abutment-plate located forward of the plunger and provided with a similarly-shaped die, the two 110 dies being in alinement and arranged to co-operate, each die being provided with a keeper axially movable, and suitable means for actuating the plunger, substantially as described. 115

4. In a wire-fence tool, the combination with a frame composed of two side bars and top and bottom plates, a plunger mounted to reciprocate in said frame, and provided with a die having a central cavity and lateral recesses, the side bars of the frame being slotted in the plane of two of said recesses, an abutment-plate mounted on the frame-bars forward of the plunger and provided with a die fashioned to correspond substantially with the die of the plunger and arranged to 125 coöperate therewith, each die having an axially-movable keeper centrally slotted, and a plate straddled by the keeper and arranged to limit the movement of the latter in one direction, and suitable means for actuating the 130 plunger.

5. In a wire-fence tool, the combination of a frame composed of side bars and top and bottom plates, the forward portions of the

side bars being slotted, a plunger arranged to reciprocate in said frame and provided with a die having a central cavity and lateral recesses, two of said recesses lying in the plane 5 of the slots in the side bars of the frame, an abutment-plate located forward of the plunger, the side bars being slotted vertically to receive said plate which is detachable at will, the said plate being provided with a die fashioned to correspond substantially with the die of the plunger, the two dies being arranged to coöperate, and suitable means for operating the plunger.

6. In a wire-fence tool, the combination 15 with a frame provided with side bars suitably connected at the top and bottom, the forward extremities of the bars being vertically grooved, an abutment-plate located in said groove and rigidly detachable, said plate having a die provided with a central cavity and lateral recesses, a plunger located in the frame in the rear of the abutment-plate and having a die fashioned to correspond substantially with the die of said plate, a link 20 pivotally connected with the rear extremity of the plunger, a hand-lever fulcrumed on the rear extremity of the frame and pivotally connected with the link forming a toggle to operate the plunger, another hand-lever pivotally connected with the toggle member at their 25

30

point of connection, the last-named lever having a part projecting forwardly from the toggle-joint, and a fulcrum mounted on the frame and engaging said lever part from above, substantially as described.

35

7. In a wire-fence tool, the combination with a frame having side bars suitably connected at the top and bottom, an abutment-plate detachably mounted in the forward extremities of said side bars, and provided with a die, a plunger mounted to reciprocate in said frame and provided with a die in alignment with the die of the abutment-plate, two links connected with the plunger at their forward extremities, a hand-lever having a bifurcated forward portion, a pin forming toggle connections between the bifurcated extremity of the lever and the plunger-links, another hand-lever pivotally connected with the said toggle-pin, and having a part projecting forwardly therefrom, and a fulcrum mounted on the frame and engaging said forwardly-projecting lever part from above, substantially as described.
